UNITED STATES PATENT OFFICE.

LEWIS D. EWING, OF AKRON, OHIO.

CONCRETE-MOLDING MACHINE.

No. 872,333.

Specification of Letters Patent.

Patented Dec. 3, 1907.

Application filed April 28, 1905. Serial No. 257,860.

To all whom it may concern:

Be it known that I, LEWIS D. EWING, a citizen of the United States, residing at Akron, in the county of Summit and State of Ohio, have invented certain new and useful Improvements in Concrete-Molding Machines, of which the following is a specification.

My invention relates to improvements in concrete molding machines, and among its several objects is to improve the hopper construction; to provide means for striking off the surplus material in the hopper after the mold box thereunder has been filled; to facilitate the adjustment of the parts of the hopper to adapt it for different forms of molds or mold boxes; to provide means for opening and closing the mold box and adjust the same for different size blocks; to improve the construction of the cores in the mold box, and to provide means whereby the molded products may be transferred directly onto a truck for final disposition.

The invention consists in certain mechanism whereby the hopper serves to convey material to the mold box. The cores and longitudinal division plates in the mold box are automatically withdrawn from the mold box after the molded product has been completed as the mold box is turned over to discharge the contents on the carrier, the carrier being located in position to receive the products. The cores and division plates automatically enter the mold box for a new charge of material in position for filling, and the motion of bringing the mold box to its original position also lowers the carrier and the molded products therewith, and places the molded product on the truck located in convenient position under the carrier.

The invention further consists in certain novel features of invention and combinations and arrangements of parts as herein-after described and claimed.

In the drawings: Figure 1 is a side elevation of the entire machine, the hopper being shown in position to receive material, and the mold box in position for discharging its contents. Fig. 2 is a broken top plan of the machine with mold box and bed plate removed on one side, and showing half top view of the mold box and bed plate on the other side. Fig. 3 is a side elevation of the complete machine showing the hopper over the mold box, the machine being in position for molding the concrete blocks. Fig. 4 is

a view of the machine showing at the left a half front elevation, and at the right a similar view as seen from the rear. Fig. 5 is a view of the hopper box, mold box, and sectional core, one half being in section. Fig. 6 is a cross section on line a—a Fig. 27. Fig. 7 is a cross section through the bottom plates of the core openings. Figs. 8 and 9 illustrate the swinging bracket hook which supports the swinging mold, Fig. 8 being a front view and Fig. 9 a side elevation thereof. Figs. 10 and 11 are detail views showing parts of the sectional cores. Fig. 12 shows in section a detail of the truss construction showing supporting pin and roller bearing pins. Fig. 13 is a cross section on line 21—21 of Fig. 26 through flexible mold and supporting bracket. Fig. 14 is a rear view as seen from the left in Fig. 13. Fig. 15 is a detail cross sectional view showing the construction of the key plate attachment to side mold box. Fig. 16 shows the key plate and hinge attached to a sectional mold. Fig. 17 is a cross section of bracket supporting hinges on the sectional mold. Fig. 18 is a view of the bracket key and key plate. Fig. 19 is a sectional view of brackets supporting stationary mold, key plate, and method of fastening to bottom plate and supporting bar. Fig. 20 illustrates the oscillating link in its connection with the frame. Fig. 21 shows the core balancing arm and stop on the frame. Fig. 22 is a top view showing sectional mold, sectional longitudinal division plate, transverse division plates and under portion of end truss supporting frame. Fig. 23 is a cross section centrally through a core. Fig. 24 is a section on line b—b Fig. 27. Fig. 25 is a cross sectional view showing attachment of oscillating link and core and balancing arm to frame. Fig. 26 is a top view in part, showing flexible sides to the molds and brackets supporting the same. Fig. 27 is a top view in part showing mold box arranged to form a multiplicity of small articles, as brick, tile, etc. Fig. 28 shows a modification wherein a strip is added to the bottom plate of the mold box for enlarging the same.

In the drawings: The numeral 1 designates the frame of the machine; 2, the swinging hopper as a whole, which is pivoted to the frame by the duplicate pairs of swing arms 3, a pair of swing arms being located at each side of the machine. These arms are extensible sectional hollow shafts or pipe

the sections being connected by any well known joint, as a bayonet lock 4, and the sections may be extended or contracted by means of the joint and band 5, by which means the arms may be held in any desired adjustment.

The top ends of the arms 3 are pivotally connected to the hopper by stud bolts 6, and the lower ends of the arms are provided with couplings 7 which have bearings on the shafts 8. The weight of the hopper is counterbalanced by weights 9.

The end members of the hopper are provided with slots 10 through which are passed bolts 11 to permit an adjustment and clamping of the side members 12 of the hopper to reduce or increase the size thereof. To the end members of the hopper are bolted or otherwise attached the bars 13. The duplicate bottom plates 14, 14' 14" are supported on and capable of sliding on these bars 13. The bottom plates 14 are provided with handles 15 on each side of the machine for conveniently operating the sliding plates of 25 the bottom. The plates form an extensible bottom, and when extended by movement of the handle 15 the raised portions or lugs 16 of the plates engage each other as the plates are drawn forward by the handles, and in the reverse motion the back edges 17 of the plates come in contact with lugs on the plates, thereby imparting the same motion to the plates in the opposite direction, thus extending or withdrawing the bottom of the hopper. When the mold box 18 has been filled from the hopper and the concrete tamped therein, the plates 14 are pushed forward by handles 15 from each side of the hopper toward the center (it being understood that when the material is dumped into the mold box the bottom of the hopper is open) thereby striking off the surplus material, and retaining the surplus in the hopper, thus avoiding waste and scattering of the surplus material over the machinery. After the extensible bottom of the hopper is closed, the hopper as a whole is carried from the mold bed on the swinging arms 3, to position to receive a fresh charge of material.

When the hopper has been re-filled it is again swung to its original position over the mold box, and the extensible bottom thereof is again opened to allow the material to fall into the mold box. As indicated in dotted lines in Fig. 4, the supplementary end members 20 of the hopper may be applied thereto, and are adjustable to contract or enlarge the size of the hopper for different size molds.

50 The mold box 18 is formed of the two end and two side mold plates 18' and 18" respectively, and one or more bottom plates 18". The sides and end plates have adjustable key plates 21 fastened at the outside thereof by bolts 21' which pass through slots

or holes provided in the plates. The side mold plate 18" is fastened to stationary bracket 22, and the bracket is in turn supported on and fastened to the bottom plate 18" by bolts 23. Mold plates 18" are also 70 fastened to supporting bar 24 carried by bed plate 43, said plates being fastened by bolts 25. One of the side plates at each side of the machine is fastened to bracket 26 which is carried by shaft 27. In operation 75 the mold is opened and closed by levers 28 on shaft 27, the mold being held in position (closed) by gravity latches 29. (See Figs. 3, 27.) The clamp hooks 29' (see Figs. 1, 3, 8, 24) are fastened on bracket 26 by pin 80 29" and clamp the carrying off board 88 on the mold while the mold is being revolved. The hooks are opened or disengaged by movement of shaft 27.

Referring particularly to Figs. 27 and 6, 85 it will be seen that the end mold plates are fastened to sliding frames or brackets 30 by bolts through the clamping plate 31. These sliding frames or brackets are supported by truss bars 32 which are adapted to move the 90 sliding frame on lines parallel to and from the mold box. There are four pairs of these bars 32 two at each side of the mold. One pair of bars is pivoted at 32' on sliding frame 30. The other ends of the bars are provided 95 with roller bearings 33, and these rollers slide in slots 34 of the supporting frame 35. One end of the other pair of truss bars 32 is pivoted on stationary pins 36 on frame 35 and the other end of said pair of bars is provided with roller bearing pins 37 located in slots 38 on the sliding frame 30. The braces or bars 32 are centrally connected at the under side of the frame by a stud 39.

The operation of the movable side and end mold plates is accomplished by the oscillation of bracket 26 attached to shaft 27. Shaft 27 extends through and beyond the outer ends of hollow shaft 27', and to the projecting ends of shaft 27 are fastened the 110 handles 28 by which handles the brackets 26 are operated through the shaft 27.

The sliding frames 30 are provided with extensions or arms 30' which are provided with roller bearing pins 30" to operate in 115 the tangent grooves 40, said grooves being located in an extended portion of the bracket 26. Thus the same movements of lever 28 in opening and closing the side mold, cause the roller bearings 30" to slide in the grooves 40 thereby opening or closing the end mold plates.

The supporting frames 35 are held in place by hinged brackets 41 and sliding brackets 35' (see Fig. 4.) The hinged bracket 41 may 125 be fastened either to the bed plate 80' or supporting bar 24. The sliding brackets 35' (see Fig. 4) are held in place on shaft 27 between brackets 26 and collars 44, and the arrangement is such that frames 35 can be 130

placed at different positions and angles to the mold box.

In the lower half of Fig. 2 is shown in top plan a portion of a mold box provided with two bottom plates 18^a and 18^b having core openings 18^c. Said bottom plates are spaced apart a sufficient distance to allow the longitudinal division plates or plate 45 to pass vertically between them. By this arrangement two blocks of concrete can be molded at the same time. By the addition of more longitudinal division plates and narrow bottom plates, a greater number of blocks may be made at one operation, such as partition blocks, slabs &c.

In Figs. 2 and 24 a portion of the mold box is shown having one of its sides provided with a sectional mold side (or a number of small mold sides) supported by bars 46, the longitudinal division plate 45 being composed of sectional parts which are attached to cross bars 46 as shown. The transverse division plates 47 are held in position by the sectional division plates 45 and the sectional molds, and do not interfere with the operation of the hopper plates above them.

In Fig. 27 is shown a top view of a mold box which is interiorly subdivided into a number of small molds by division plates 48 and transverse division plates 49 for the purpose of molding tile, brick, or other small articles. The longitudinal plates 48 are attached to cross bars 46 (see Fig. 24). The plates 48 are slotted for the purpose of receiving and holding the transverse plates 49. Metal bars 51 and 52 are fastened to the sides of both series of division plates to impart rigidity thereto.

In Fig. 26 is shown a portion of a mold box having two flexible sides 53 for the purpose of molding circular or curved bodies. These sides are held in place by brackets 53' and 53''. The inside brackets 53' are fastened on a separate board 54 which board is held in place by end mold bars 55. Mold bars 55 swing on brackets 41 and are opened or closed by pin 30'' in groove 40 as before described, being operated from lever 28. Projecting lugs 56 on mold bars 55 are provided with slots 56' and a bolt 56'' passes through the slot to retain the end mold in position while the mold box is being turned over, as will be described. The flexible mold is formed by attaching flexible strips 53 to brackets 53' and 53'' and a brace or stiffening plate 57 (Figs. 13, 14) is placed against said strips. Portions of the edges of said strips or plates are cut away to allow for bending, and the remaining portions or lugs are turned over the upper and lower edges of the strips so as to hold the metal plates or braces in place (Fig. 14).

In Fig. 6 the attachment of the various bottom plates of the mold box to the bed plates 80' is illustrated. The end of the bot-

tom plate 58 is dovetailed and fits into a recess in the bed plate, being held in place through bolts 59 in clamping bar 60. By loosening the bolts 59 the bottom plates may be adjusted to vary the size of the blocks desired. The wall of the next blocks may be increased in thickness by inserting sectional bottom plate strips as 120 in Fig. 28.

In Fig. 28 the bottom plate 119 of the core box may be provided with a strip 120 added thereto for the purpose of enlarging the area of the wall of the block.

As clearly shown in Fig. 5 the core 61 is provided with a tapering central portion. The sectional side pieces 62 are made to fit on the body of the core with corresponding tapering edges and are provided with two projecting lugs 62' and 62'' (see Fig. 23) which are provided with slots 63, 63' located at a slight angle to the perpendicular, through which slots the bolts 64 are passed. In operation, a pull on the cross bar 65 draws the central portion of the core and as the bolt 64 moves along the slots 63, 63', it draws the sectional sides closer together and releases the sides from the material being molded. The cores are fastened to the bars 65 by bolts 66, and bar 65 is attached to the truss bar 67, as shown in Figs. 4 and 5 by plate 66' and bolts.

The truss bars 67 are carried to and from the mold box by trusses 68 (Figs. 1 and 4). Cross braces 69 are fastened to truss bars 67. Cross braces 69 are fastened to the truss bars by stud pins 70 on which pins the braces revolve. The opposite ends of the truss bars are provided with roller bearing pins 71 which move between slides 72 fastened to projecting lugs on the underside of bed plate 80'. The corresponding braces 69' are supported by and revolve on hollow shaft 27' (Figs. 2 and 20). The opposite ends of the braces are provided with roller bearing pins 71' which move between slides 67' on truss bars 67. Braces 69' having attached to their sliding ends projecting pins or supports 73 which in operation come in contact with stops 74 and thereby assist in holding the core 61 and carrying device at any desired position (see Figs. 1 and 3).

The truss bars 69 and 69' are united centrally by pins 75 and thus complete the trusses, at each side of the machine. The heads of the pins 75 support the end of the operating arms 76. These arms 76 are provided at their opposite ends with stud pins 77 which slide in slots 77' in weight arms 78, which arms carry the weights 79.

In operation when the mold box is in position shown in Fig. 1 the operating arms 76 rest on the adjustable stops 80 on arms 78. The resistance thus given by the lifting of the weights 79 assists to keep the cores 61 in position while the mold box is being filled and also assists in overturning the mold box until

the weights hang perpendicularly, in which position the weights remain until pins 77 in the ends of the arms 78 come in contact with the end of the slot 77' therein, when said 5 weights will again balance the load, and are carried forward until the arms 78 come in contact with stops 80 (Fig. 21) on the frame of the machine. When the arms contact with this stop they are held and the forward 10 movement of the bed plate 43 causes the cores to be drawn from the mold box to position for discharging, by balancing the weight of the core carrying device.

The cores are made to reenter the mold 15 box by the above described pins 73 coming in contact with stops 74 assisted by the weights 79. When said weights are hanging perpendicularly, the overturning bed plates are balanced over the turning pins.

20 The bed plates 43 are connected to the frame 1 by links 81. Figs. 20 and 21 show how the connecting link 81 is attached to the frame, by pins 82 and also shows the weight arms supported on pins 82. The other end 25 of the connecting link 81 supports the hollow shaft 27' (Fig. 2) on which the bed plates revolve.

It will be observed in Fig. 3 that a portion of the mold box projects beyond the pins 82, 30 thereby partially balancing the weight and lessening the labor that would otherwise be required to turn over the mold box. The weight is carried on pins 82 until connecting links 81 come in contact with the frame support (Figs. 1 and 20). The weight is then transferred to the hollow shaft 27' on which the bed plates 80' revolve until in position for discharging the contents of the mold box.

When the connecting link 81 rests on frame 40 support as shown in Fig. 20 with the bed plates resting on both points of the connecting links, the mold box is in an advantageous position for facing or veneering the blocks with select material.

45 The bed plates are provided with handles 84 which are used in turning over the mold box. The extended portions of the plates are provided with slots 85 and adjustable pins 86 are fastened in said slots at the point 50 required to bring the carriers 87 against the carrying board 88 (Fig. 1). In operation, as the bed plates are turned over by handles 84 to discharge the contents of the mold box, pins 86 engage hooks 89 and thereby lift the 55 carriers until they come in contact with carrying boards 88, when a downward pressure on handle 28 opens the mold box and contents are deposited on the carrying board 88.

The returning of the mold box to its first 60 position lowers the carriers and places the carrying board on the truck 90 beneath the machine, thereby saving the handling of the material. The weight of the material as it rests on the carriers greatly assists in lifting

the mold box in the first portion of its return 65 movement.

The hooks 89 are held in position by tension guides 91 and the hooks are attached to arms 92 by bolts 93. The arms 92 are connected to brace arms 94 and 95 as shown in 70 Fig. 2 by shafts 95' 96, 97 and 98. Shafts 95 and 96 revolve on bearings in the frame, and one end of shafts 97 and 98 are connected by bars 99, the other end projects beyond the brace arms 94 and 95 and supports 75 the carrier bars 100.

The tamping platform 101 revolves on shaft 102 and the arm 103 serves as a support for the planks of the platform. Gravity supports 104 support the platform while in 80 use and the weights 105 are provided to balance the platform. When the platform is thrown back out of the way for discharging the contents of the mold box the spurs 106 engage ratchets 107 and by moving the platform forward the truck is moved forward for 85 the next block to be molded.

The construction of the shafts connecting the ends of the machine are such that the machine can be lengthened for the molding 90 of sills, and other long articles. To the end frames 108 are attached sectional sleeves 109, 110 111, interior of which are shafts corresponding in thickness to openings in said sleeves. The ends of the sectional sleeve 95 shafts are slotted lengthwise for a short distance with a short transverse slot at the end of the same for contraction by clamps 112 113 and 114. The ends of the sectional 100 shafts are placed between the end frames and clamped in place by bolts which fasten the frames together.

In Fig. 7 a cross section of the bottom plates 130, 131, 132 and 132' of the mold box is shown illustrating how the adjustable 105 pieces 115 slide in grooves 116 for the purpose of arranging the core openings. The pieces are held in place by clamping bars 117 which are bolted to the sectional pieces by bolts 118 for the purpose of arranging different core openings in the blocks, said plates 115 may be inserted to form an indentation in the lower side of the block, as at the right side in Fig. 7, or placed to form a smooth surface on the block, as at the left in said figure. 115

What I claim and desire to secure by Letters Patent is:

1. In a concrete molding machine, the combination with a mold box of a hopper having adjustable sides and adjustable extension members, and provided with an extensible bottom.

2. In a concrete molding machine, the combination with a mold box of a swinging hopper having adjustable sides and adjustable end members, and provided with an extensible bottom.

3. The combination with a mold box of a

- swinging hopper, provided with adjustable sides and adjustable end members, and a bottom formed of plates adapted to slide one over the other to open or close the bottom of the hopper.
4. In a machine for molding concrete, a hopper provided with adjustable sides and an extensible bottom, a mold box, and means consisting of pivoted bars for swinging said hopper to and from the mold box.
5. The combination with the mold box of a concrete machine, of a hopper having its sides adjustable and provided with extensible bottom plates, and adjustable supporting oscillating arms provided with balancing weights for swinging the hopper to and from the mold box.
6. The combination in a concrete molding machine of a hopper provided with adjustable sides, adjustable extension sliding members forming the bottom thereof, adjustable extension sliding end members and means for holding the same in adjusted position, and means to convey the hopper to and from the mold box.
7. The combination in a concrete molding machine of a mold box, a hopper provided with extensible side and end members, an extensible bottom, side bars for supporting and guiding the extensible bottom, and oscillating arms supporting the hopper for swinging said hopper to and from the mold box.
8. The combination in a concrete molding machine, of an oscillating hopper, a mold box and cores therein, means for turning said mold box to discharge its contents, and means for automatically withdrawing the cores therefrom as the box turns.
9. The combination in a concrete molding machine, of a hopper a mold box and collapsible cores therein, said box having sectional sliding bottom plates, means for overturning said box to empty its contents and automatically withdraw the cores therefrom, and means for reentering said cores into the box as the box is righted.
10. The combination in an oscillating concrete molding machine of a hopper, a mold box and collapsible cores therein, said box having flexible side mold plates means for turning said mold box to empty its contents, and automatically withdraw the cores therefrom, and means to counterbalance the weight of the cores and core carrier.
11. The combination in a mold box of collapsible cores and division plates therein, said box having flexible side mold plates and sliding bottom plates, means for withdrawing said cores and plates therefrom as the box is overturned and to reenter the same therein, and means to counter balance the weight of said cores.
12. The combination in a machine of the character described of an oscillating hopper,
- a mold box, means for overturning the box, and means for transporting its contents to a movable vehicle.
13. The combination in a mold box, of collapsible cores and division plates therein, sectional sliding bottom plates and flexible side mold plates adapted to make various curves for molding concrete blocks.
14. The combination in a concrete molding machine of a mold box having flexible side plates and ends, brackets supporting said sides and ends sliding sectional bottom plates, means for contracting or enlarging the mold box and a shaft for operating said means.
15. The combination in a molding machine of a mold box having a movable side plate, movable end plates, and sectional bottom plates, pivoted cross bars connected to the end plates of the box, and means for moving said bars to increase or decrease the area of the box.
16. The combination in a concrete molding machine of a mold box having end plates and stationary and movable sides, pivoted cross bars connected to the sides, a sliding frame connected with the cross bars, a shaft with a tangentially slotted bracket thereon, a pin on the sliding frame engaging said groove, and a handle on the shaft.
17. The combination in a concrete molding machine of a mold box having a movable side and movable ends, an oscillating bracket having a groove therein, a sliding frame connected to the mold box having a pin in said groove, a shaft supporting the bracket, and a handle on the shaft.
18. In a mold box the combination of a bed plate, a hinged bracket and a sliding frame connected to the movable side and ends of the box, pivoted truss bars connected to the sliding frame, and means for operating said bars to open or close the mold box.
19. The combination in a mold box of a bed plate, a hinged bracket and a sliding frame connected to the movable side and ends of the box, pivoted truss bars connected to the sliding frame, a roller bearing in the frame, a shaft carrying a tangentially grooved bracket, said roller located in the groove, and a handle to the shaft.
20. The combination in a mold box of a bed plate, a hinged bracket and a sliding frame connected to the movable side and ends of the box, said sides being flexible, a roller bearing in the frame, a shaft carrying a tangentially grooved bracket, said roller located in the groove, and a handle to said shaft.
21. The combination in a mold box having movable ends, means for operating said ends, of sectional bottom plates and flexible side plates to said box provided with adjusting means.
22. The combination in a mold box having

movable ends, adjustable supporting means for said ends, sectional sliding bottom plates and adjustable flexible side plates to said box, and operating means therefor.

23. The combination in a molding machine and with the frame thereof of a revolving bed plate and mold box thereon, cores in said mold box trusses connected to said bed plate and having their opposite ends connected to a truss bar, said trusses pivoted together at their centers, an operating arm connected to said pivot, and means for operating said trusses through the operating arm.

24. The combination in a molding machine of a revolving bed plate, a mold box, cores in said box trusses connected to said plate and having their opposite ends connected to a truss bar, said trusses pivoted together at their centers, an operating arm connected to said pivot, a weight arm connected with the operating arm, and also connected to the bed plate.

25. In a molding machine, the combination with a mold box having flexible side plates and sliding bottom plates, of a collapsible core, operating means therefor, and means actuated from the machine to collapse said core.

26. In combination, a mold box having flexible side plates, sectional sliding bottom plates, and a core in said mold.

27. In a machine as described, the combination of a mold box comprised of flexible side plates and sectional sliding bottom plates, with a collapsible core, and means for collapsing the same.

28. The combination in a molding machine, of a mold box and cores therein, means for withdrawing said cores, bed plates to the box, means for overturning said bed plates and box, a carrying board for receiving the contents of the box, and means for transporting said board and contents.

29. The combination in a concrete machine of a mold box having stationary and movable sides and end plates, a sliding frame connected to said plates, pivoted cross bars connected to said frame, a shaft with a tangentially slotted bracket thereon, a pin on the sliding frame engaging said slotted bracket, and a handle on the shaft.

30. In a machine as described, the combination with a mold box and a block therein, of reversible members adapted to seat in said box, and project within the block to form a depression in the web of the block.

31. In a machine as described, the combination with a bottom plate of a mold box and block therein, and an invertible member adapted to seat in the box and project within said box to form a depression in the block.

32. An adjustable sectional bottom plate provided with invertible members, said members adapted to project within the mold and

form an indenture within the web of the block.

33. The combination with a mold and block therein of a sectional bottom plate consisting of reversible members adapted to seat in the mold and project within therein to form a depression in the block.

34. The combination with a mold box, of a swinging hopper having adjustable side and end members and provided with an extensible bottom.

35. The combination in a molding machine, of a mold box having movable sides, pivoted cross bars connected to the sides, a sliding frame connected with the cross bars, a shaft with a bracket thereon, and means on the sliding frame engaging said bracket.

36. The combination in a mold box, of a bed plate, movable sides and ends to the box, a bracket and frame connected to the movable sides and ends, a sliding frame bars connected to the sliding frame, and means to operate said bars to open or close the mold box.

37. A concrete molding machine comprising a mold box, a hopper having extensible sides and bottom, and oscillating arms for swinging said hopper to and from the mold box.

38. A concrete molding machine comprising a mold box, a hopper having extensible sides and bottom, swinging arms for conveying the hopper to and from the mold box, and means for turning the mold box to discharge its contents.

39. A concrete molding machine comprising a frame, a revolving bed plate and mold box thereon, trusses connected to said bed plate and having their opposite ends connected to a truss bar, the trusses being pivoted together, an operating arm connected to the trusses, and means for actuating the operating arm.

40. A concrete molding machine comprising a mold box, a hopper adapted to convey material thereto, a carrier, and means for automatically causing the mold box to discharge the molded contents on the carrier.

41. A molding machine, comprising a mold box, movable cores in said box, a hopper to convey material to the mold box, a carrier, and means for automatically withdrawing the cores from the mold box and depositing the molded product on the carrier.

42. A molding machine comprising a mold box, adjustable cores and division plates in said box, a hopper for automatically conveying material to the mold box, a carrier, and means for automatically withdrawing the cores and division plates from the mold box and depositing the molded product upon the carrier.

43. A molding machine comprising a mold box, adjustable cores and division plates therein, a carrier, means for automatically

5 withdrawing the cores and division plates from the box and depositing the molded product on the carrier, and means for automatically reentering the cores and division plates in the mold box.

10 44. A molding machine comprising a mold box, adjustable cores and division plates therein, a pivoted hopper for supplying the mold box, means for automatically with-
drawing the cores and division plates from the box, and means for reentering the same in the mold box when the box is cleared of its molded product.

15 45. A molding machine comprising a mold box, a hopper to supply the same, adjustable cores and division plates in the mold box, a carrier, means for withdrawing the cores and division plates from the box and depositing the molded product upon the carrier, and
means for reentering the cores and division plates in the box.

20 46. A molding machine comprising a mold box, a swinging hopper to supply the same, adjustable cores and division plates in the mold box, a carrier, means for withdrawing the cores and division plates and depositing the molded product upon the carrier, and means for returning the parts to their original position.

25 30 47. A molding machine comprising an adjustable mold box, a swinging hopper to supply the mold box capable of adjustment to suit the mold box, means for conveying the surplus material from the mold, and means

for transferring the molded product from the 35 mold box for final disposition.

48. A molding machine comprising a frame, an adjustable swinging hopper pivoted thereto provided with a counter balance, a mold box to receive material from the hopper, and means on the hopper for retaining the surplus material therein after the mold box has been filled.

49. The combination with a mold box adjustable in each direction, adjustable cores 45 and division plates for use in the mold box, of a hopper to supply material to the mold box, said hopper being adjustable to suit the mold box.

50. A molding machine comprising a frame, a truck beneath the frame, an adjustable mold box, an adjustable swinging hopper to supply the mold box, a carrier, adjustable cores and division plates for the mold box, means for withdrawing the cores and 55 division plates from the mold box and depositing the molded product upon the carrier and thence upon the truck, and means for reentering the cores and division plates in the mold box and returning the parts to their 60 original position.

In testimony whereof I affix my signature in presence of two witnesses.

LEWIS D. EWING.
